UNITED STATES PATENT OFFICE.

CHARLES F. HANINGTON, OF NEW YORK, N. Y., ASSIGNOR TO THE
MECHANICAL DOOR HINGE CHECK COMPANY, OF SAME PLACE.

DOOR-CHECK.

SPECIFICATION forming part of Letters Patent No. 629,247, dated July 18, 1899.

Application filed October 19, 1898. Serial No. 693,980. (No model.)

To all whom it may concern:

Be it known that I, CHARLES F. HANINGTON, a citizen of the United States, residing in the borough of Manhattan, city of New York, 5 county and State of New York, have invented certain new and useful Improvements in Mechanical Door-Checks, of which the following is a specification.

My invention relates to various new and useful improvements in mechanical door-checks; and the object of the invention is to simplify the construction and improve the operation of such devices.

In carrying out my invention I provide a hinge of any suitable type having two leaves and a barrel and combine therewith mechanical checking devices which will be simple in construction, effective in operation, durable in use, capable of being easily reached for purposes of repair, and wherein when desired the checking action may be discontinued.

The type of device to which my invention particularly relates is that shown and described in my Patent No. 601,830, dated April 25, 1898, and the present improvements are designed to simplify the construction and improve the operation of that device.

In order that my invention may be better understood, attention is directed to the accompanying drawings, forming part of this specification, in which—

Figure 1 is a side elevation, partly in section, of an ordinary door-hinge equipped with my present invention, the hinge being represented in a closed position; Fig. 2, a similar view showing the two leaves separated at an angle of ninety degrees; Fig. 3, a horizontal sectional view on the line 3-3 of Fig. 1, showing the position of the hinge when the door is entirely open; Fig. 4, a view similar to Fig. 3, illustrating the position of the parts when the hinge has been closed to the checking position; Fig. 5, a perspective view of the checking-pawl and the locking-dog carried thereby; Fig. 6, a sectional view through the checking-pawl, illustrating the latch for the locking-dog; Fig. 7, a side elevation, partly in section, of a modification illustrating the hinge-leaves in an open position and in dotted lines the 50 position of the checking-pawl after it has been tripped; Fig. 8, a section on the line 8-8 of

Fig. 7; Fig. 9, a section on the line 9-9 of Fig. 7; Fig. 10, a section on the line 10-10 of Fig. 7, and Fig. 11 a detail view of a further modification.

55

In all of the above views corresponding parts are represented by the same numerals of reference.

1 is a hinge-barrel, and 2 3 are the two leaves. One of such leaves is secured to the frame of the doorway or jamb, and the other leaf is secured to the door. In the drawings I illustrate the barrel 1 as being carried with the leaf 3, and I illustrate the leaf 2 as being pivoted upon the ordinary pintle 3', (see Fig. 60 4,) which is mounted in said barrel. Carried by the barrel is a sleeve 4, in which is formed a slot 5, at the end of which slot is a shoulder 6, upon which is imposed the checking thrust or strain. The collar 4 is secured to the pintle or barrel in any suitable way, as by screws 65 70.

Extending parallel with the slot 5, above the shoulder 6, is a shorter slot 8, which communicates with slot 5 and is provided above and in front of the shoulder 6 with a 75 curved cam-surface 9. It will be understood that instead of providing a collar secured to the pintle or barrel, said collar carrying a shoulder 6 and a cam-surface 9, it will be possible to make use of a separate shoulder 80 6 and a separate cam-surface 9, secured independently to the pintle or barrel, as shown in Fig. 11. Adapted to work in the slots 5 and 8 is a checking-pawl 10, which in this instance is carried on the leaf 2, within a recess 85 11, formed in said leaf, and upon a sufficiently heavy screw 12. A small leaf-spring 13 bears beneath the locking-pawl 10 and normally tends to elevate the same. Secured to the leaf 2 and in engagement with the locking-pawl 10 is a checking-spring 14, which in this instance is a leaf-spring secured to said leaf by the screws 15 and 16, the latter working in a slotted opening 17, so as to allow for slight movement of said spring when the latter is bowed at its center. The checking-pawl 10 is capable of movement within the recess 11 and parallel with the spring 14. Said checking-pawl is also capable of movement outward from the hinge-leaf 2 against the 90 tension of the spring 14, and to allow of this movement the said checking-pawl 10 is some 95 100.

what loosely mounted on the pivot 12, as will be understood. In order to lock the pawl 10 in a normally-depressed position, so as to cause it to engage the shoulder 6 when the leaves of the hinge are brought together, I provide (in the form of device shown in Figs. 1 to 6) a locking-dog 18, which is carried by said pawl in a recess 19, formed on the under side thereof. This locking-dog is mounted on a small pivot 20 and is provided with a projecting finger 21, which engages in a recess 22, (see Figs. 3 and 4,) formed on the inner side of the spring 14. When the locking-dog 18 is thus engaged in the recess 22, its inner end 23 extends outwardly with respect to the face of the checking-pawl 10, so that when the two leaves of the hinge are moved relatively thereto the rear end 23 of the locking-dog will engage the shoulder 6 before the checking-pawl engages said shoulder, whereby the finger 21 will be disengaged from the recess 22 to unlock the checking-pawl 10.

In order to reset the locking-dog 18 when the hinge is again opened and to cause the finger 21 to again engage the recess 22 to lock the checking-pawl 10 in its depressed position, I provide a pin 24, which extends diametrically through the barrel and pintle, as shown in Fig. 4, and which is arranged in the path of movement of the inner end of the locking-dog 18. This pin 24 is formed on the end of a screw 25, having a milled thumb-head 26, by which the said pin may be withdrawn out of the path of movement of the locking-dog when it is not desired to reset the same and when a checking action is to be avoided. In order to secure the locking-dog 18 in its operative position to maintain the checking-pawl 10 normally depressed, I prefer to make use of a small latch 27, (see Fig. 6,) carried in a chamber 28 in the checking-pawl and normally pressed outward by the spring 29 to engage a recess 30 in the locking-dog 18. If desired, the operative parts of the check may be concealed by a casing 31, secured to the barrel 2 by small screws 32 and provided with a slot 33 therein, in which slot may work the inner end of the checking-pawl, as will be understood. To reset the checking-pawl after the same has been moved upward by the spring 13 by the engagement between said pawl and cam-surface 9, I prefer to form the inner end of said pawl where the same engages with said cam-surface with a beveled or curved portion 34, by reason of which a smooth engagement will be secured in the resetting operation.

The operation of the device is as follows: Normally the inner end of the checking-pawl 10 will work in the slot 5, the said pawl being locked in a depressed position against the tension of the spring 13 by the engagement of the finger 21 of the locking-dog 18 with the recess 22 in the checking-spring 14. When the door is closed by hand or by a suitable spring device, the two leaves 2 and 3 will be moved almost together, so as to first engage

the rear side of the locking-dog 18 with the shoulder 6 to disengage the finger 21 from the recess 22, and thereby free the checking-pawl. Before the spring 13 can force the checking-pawl 10 upward, however, into the slot 8 the rear end of the checking-pawl 10 will have engaged the shoulder 6, and the friction thus produced between those parts will prevent upward movement of the pawl. This engagement between the inner end of the checking-pawl and the shoulder 6 takes place immediately before the door is closed, and the strain will be thus thrown upon the checking-spring 14, which will be caused to buckle outward at its center by the slight movement of the checking-pawl against the spring. An elastic checking action is thus secured. When the door has rebounded, the inner end of the checking-pawl 10 will be disengaged from the shoulder 6 to relieve the friction between the two, and the spring 13 will then immediately elevate the said pawl and cause its inner end to work in the slot 8 to thus allow the leaves to engage together, as shown in Fig. 1, and to allow the door to close. When the door is reopened, the inner end of the checking-pawl will engage the cam-surface 9 and said pawl will be moved downward into the slot 5. Immediately thereafter the inner end of the locking-dog 18 will engage the end of the pin 24 to cause the finger 21 to again enter the recess 22 and lock the pawl 10 in its depressed normal position. At the same time the latch 27 will engage the recess 30 in the locking-dog, so that the latter will also be locked in its normal position ready for a further checking operation.

When it is desired that the checking action should not take place, the thumb-screw 26 is withdrawn with the pin 24 from the path of movement of the locking-dog 18. When this is done, it will be seen that the locking-dog 18 will not be reset upon the opening of the door, so that when the door closes there will be no engagement between the pawl 10 and the shoulder 6, since the spring 13 will have elevated the pawl into line with the slot 8 before such engagement can take place.

Instead of making use of a locking-dog carried by the checking-pawl as described a separate locking device may be used, as shown in Figs. 7 to 10, which will be preferable, since it may be made much larger and stronger without in any way affecting the compactness of the device. With this form of my device the checking-pawl is pivoted to the leaf 2, bearing against the checking-spring, with its free end working in the slots 5 and 8, engaging the shoulder 6, and being reset by the cam-surface 9, as heretofore.

A separate locking-lever 34 is employed, pivoted on the leaf 2 by a screw 35 and engaging the locking-pawl on the other side from the checking-spring. For this purpose the leaf is cut entirely through at 36, and the checking-pawl works directly between the checking-spring and locking-lever 34. The latter

is made, preferably, of flat steel and is secured at its other end from the pivot on a screw 37, working in a slot 38. The lever 34 is provided with a finger 39, working in a slot 40, cut in the sleeve 4 immediately below the slot 5. The said lever is also provided on its under side with a lug 41, (shown in dotted lines, Fig. 7, and in full lines, Fig. 10,) having a recess therein forming a shoulder 42. Pending from 5 the checking-pawl 10 is a hook-like projection 43, adapted to engage the shoulder 42, and thereby hold said pawl in its normal position in line with the shoulder 6. The lever 34 is maintained in a position to keep these elements in engagement by a spring 44. In order to move the lever 34 to release the shoulder 42 from the hook 43 to trip the pawl, I provide a wedge-shaped stud 45' in the slot 40, which engages the finger 39 and throws it 10 backward immediately before the end of the checking-pawl strikes the shoulder 6, as in the device shown in Figs. 1 to 6. A small pivoted latch 45 is used to hold the lever in a retracted position when it is desired to dispense with a checking operation.

With the device described in the patent referred to the sleeve carrying the shoulder and resetting-cam is movably mounted with respect to the barrel, and the checking-spring 15 is connected to said sleeve. By carrying the sleeve or the resetting-cam rigidly on the barrel or with respect thereto and by mounting the checking-spring on one of the leaves I secure greater simplicity and increased efficiency. By also providing means whereby the checking mechanism may be disconnected, as explained, I also materially increase the capacity of devices of this type.

Having thus described my invention, what 20 I claim as new, and desire to secure by Letters Patent, is—

1. In a door-check, the combination with the two hinge-leaves, one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, and a spring 25 for resisting said movement whereby an elastic checking action will take place, substantially as set forth.

2. In a door-check, the combination with the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane 30 parallel with the closing movement, a spring for resisting said movement whereby an elastic checking action will take place, and means for automatically moving the checking-pawl out of the plane of said shoulder on the rebound, substantially as set forth.

3. In a door-check, the combination with the hinge-leaves one of which carries a barrel, of

a shoulder movable with said barrel, a checking-pawl carried by the stationary leaf and adapted to engage said shoulder before the door is closed, said checking-pawl being movable with respect to its leaf in a plane parallel with the closing movement, a spring for resisting said movement whereby an elastic checking action will take place, means for automatically moving the checking-pawl out of the plane of said shoulder on the rebound, and means for resetting the pawl by the opening of the hinge-leaves, substantially as set forth.

4. In a door-check, the combination with the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, a spring for resisting said movement whereby an elastic checking action will take place, and a cam- 85 surface with which the pawl engages upon the opening of the leaves, and by which the pawl will be reset to again engage the shoulder upon the closing movement, substantially as set forth.

5. In a door-check, the combination with the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, and a leaf-spring carried by the movable leaf for resisting the movement of said pawl, said spring 100 having sufficient play to allow of its buckling at the center, substantially as set forth.

6. In a door-check, the combination with the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, a spring 115 for resisting said movement whereby an elastic checking action will take place, and a locking-dog carried by the pawl and normally locking said pawl in a position to engage the shoulder, substantially as set forth.

7. In a door-check, the combination with the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, a spring for resisting said movement whereby an elastic checking action will take place, a locking-dog 125 carried by the pawl and normally locking said pawl in a position to engage the shoulder, and means for releasing said locking-dog when the pawl engages the shoulder, whereby upon the

rebound the pawl will be moved out of its engagement with the shoulder to allow the closing of the door, substantially as set forth.

8. In a door-check, the combination with the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, a spring for resisting said movement whereby an elastic checking action will take place, a locking-dog carried by the pawl and normally locking said pawl in a position to engage the shoulder, and an adjustable pin for resetting said locking-dog, said pin being movable with respect to the locking-dog for the purpose mentioned, substantially as set forth.

15 5 35

15 10 In a door-check, the combination with the two hinge-leaves one of which carries a barrel, a shoulder movable with said barrel, a checking-pawl carried by the stationary leaf and adapted to engage said shoulder before the door is closed, said checking-pawl being movable with respect to its leaf in a plane parallel with the closing movement, a spring for resisting said movement whereby an elastic checking action will take place, a locking-dog carried by the pawl and normally locking said pawl in a position to engage the shoulder, means for releasing said locking-dog when the pawl engages the shoulder, whereby upon the rebound the pawl will be moved out of its engagement with the shoulder to allow the closing of the door, and means for automatically resetting the pawl and for resetting the locking-dog, substantially as set forth.

20 15 40

20 20 45

20 25 50

20 30 55

9. In a door-check, the combination of the two hinge-leaves one of which carries a barrel, of a shoulder movable with said barrel, a checking-pawl carried by the stationary leaf and adapted to engage said shoulder before the door is closed, said checking-pawl being movable with respect to its leaf in a plane parallel with the closing movement, a spring

for resisting said movement whereby an elastic checking action will take place, a locking-dog carried by the pawl and normally locking said pawl in a position to engage the shoulder, and an adjustable pin for resetting said locking-dog, said pin being movable with respect to the locking-dog for the purpose mentioned, substantially as set forth.

10. In a door-check, the combination with the two hinge-leaves one of which carries a barrel, a shoulder movable with said barrel, a checking-pawl carried by the stationary leaf and adapted to engage said shoulder before the door is closed, said checking-pawl being movable with respect to its leaf in a plane parallel with the closing movement, a spring for resisting said movement whereby an elastic checking action will take place, a locking-dog carried by the pawl and normally locking said pawl in a position to engage the shoulder, and a latch for securing said locking-dog in its normal position, substantially as set forth.

This specification signed and witnessed this 15th day of September, 1898.
